UNITED STATES PATENT OFFICE.

THADDEUS STEPHENS CASNER, OF PLAINFIELD, NEW JERSEY, ASSIGNOR TO RADIO ELECTRIC CLOCK CORPORATION, OF NEW YORK, N. Y., A CORPORATION OF DELAWARE.

COMPOUND-PENDULUM CLOCK.

Application filed June 17, 1926. Serial No. 116,696.

This invention relates to clocks of the pendulum type and particularly to clocks of this type which receive their driving force from electro-magnetically operated devices.

5 It is an object of this invention to provide improved driving mechanism for such a clock.

Another object is to provide driving mechanism operating directly on the pendulum of the clock which shall function at intervals to give the pendulum renewed momentum, the intervals between impulses being of such length as to maintain the amplitude of swing of the pendulum sufficiently 15 long for operating the parts driven thereby and yet not so short as to interfere unnecessarily with the free swinging of the pendulum.

Another object is to provide actuating 20 mechanism which is so constructed and arranged that when it does operate, it shall, in imparting renewed momentum to the pendulum, interfere only slightly with the free swinging of the pendulum.

25 Another object is to provide such an actuating mechanism which has few parts, and those of a simple nature, so that it will not readily get out of order, can be easily repaired, and which is readily accessible for 30 inspection and oiling.

The invention will be described as applied to a master clock though it is apparent that it is adapted to other uses. One form of the invention is illustrated in the accompanying 35 drawing by way of example, the single figure showing in front elevation a compound pendulum clock in which the invention is embodied.

Referring to the drawings 10 indicates a 40 frame or support which may be in the form of an angle member, having a horizontally disposed base portion 11 and a vertically disposed back 12. A pendulum 13, preferably of the compound type, is supported for 45 oscillation on a pair of adjustable pins 14 having hardened steel points which ride on corresponding jewels 15. The jewels are set in a horizontally extending support bracket 17 rigidly secured to the back 12 of the frame 50 10. The pendulum has a lower weight 18 and upper weight 19 and between them an enlarged portion 20 provided with an opening 21 to accommodate the support 17.

The pendulum carries on a pivotal pin 25 55 a push rod or pawl 26 which is balanced to a

certain extent by a weight 27 to cause the operative end to press only lightly on a wheel which it is intended to move. The operative end of the push rod 26 carries a pin 28 for bearing on and engaging the teeth 60 of a rotatable toothed wheel 30 fixed to a shaft 31 which is supported at one end in the frame back 12 and at the other end in an angled bracket 32 secured to the frame. The wheel 30 preferably has sixty teeth and when 65 the pendulum makes 120 beats, or 60 beats on each side of a vertical line through its support, per minute, the toothed wheel through push rod 26 is moved one complete revolution. A dog 34 which is practically 70 balanced about a pin 35 but which is slightly biased by any suitable means, as by a weighted end, so that its operative end engages the wheel, serves to prevent backward 75 movement of the wheel when it is moved by the push rod.

The wheel 30 in its rotation carries with it a contact arm 37 having a contact 38. The arm 37 may be arranged in any well known manner to move with the wheel, being either keyed to shaft 31 or secured to the side of the wheel 30. A guide 39 on the arm 37 serves to guide the contact 38 into engagement with a relatively fixed contact 40 supported on a light spring 41 carried on an insulating block 42 fast on the frame. The contact 38 is so related to the wheel 30 as to make connection with contact 40 when the pendulum is making a stroke to the right on a beat to the right of the support, and to 80 break connection just before the stroke is completed.

The contacts 38 and 40 are in circuit with a source of electrical energy 50 and an electro-magnet 51, also carried by the frame 95 back 12 and when the contacts connect, the electro-magnet is energized. From the nature of the mechanism described, it will be seen that the contacts connect to energize the magnet once for each revolution of the toothed wheel 30, or once a minute.

The shaft 31 is adapted and intended to serve as a carrier for the second hand of the clock as well as to drive the minute and hour hands through the usual train of clock gearing. The contacts 38 and 40 are likewise adapted to close a circuit 49 through one or more electro-magnetically driven devices, which may be secondary clocks.

A movable armature 55 is carried on a 110

pivot 56 adjacent the electro-magnet and is adapted to be attracted by the poles of the magnet when the magnet is energized. A soft iron plate 57 may be inserted in the armature bar 55 to cause it to be more strongly attracted to the electro-magnet. The whole bar 55 is not made of soft iron for the reason that it serves the further purpose of actuating the pendulum, as will be presently described, and as an actuating member it should be made of a harder iron or steel.

The bar 55 is extended beyond the magnet and at its outer end pivotally supports as by pin 59, a driving member or pawl 60. The pawl has an overhanging portion 61 on one side of the pin which tends to cause the upper end of the pawl to move to the right as viewed in the drawings. To check this movement of the pawl a projection 62 which preferably is a spring riveted or soldered to the pawl, is provided for the other side of the pawl and engages a fixed stop, such as the lower portion of bracket 17. The spring not only checks the movement of the pawl to the right of the position shown but tends to cause the pawl to move to the left to the dotted line position when the pawl is pushed up by the armature. The pawl has a projection 65 on its upper end and this projection engages the upper surface of a pin 70, when the pawl is moved to the left. The pin 70 is fixedly secured to the enlarged central portion of the pendulum laterally of the pivot 17 of the pendulum. The pin by this arrangement has a general vertical movement while the pendulum in most of its parts may be said to have a horizontal movement.

A spring 54 may be attached to the armature and frame to assist the action of gravity in returning the armature to its unattracted or off position. The armature is stopped in its outward or downward movement by a stop 58 fixed to the frame. The stop 58 is located at such a point that the movement of the armature is halted before the pendulum has completed its movement to the left on the right beat to carry pin 70 to its lowermost position. This is done for the purpose of allowing the pin 70 to move away from projection 65 on pawl 60. When this occurs the pawl drops over to the right due to the unbalanced weight portion 61 thereon to take projection 65 out of the path of pin 70 until the armature is again attracted by the magnet. However, it will be understood that the contacts 38 and 40 are moved apart to allow magnet 51 to be de-energized just before the pin 70 completes its upward movement, caused by the right swing of the pendulum, which leaves projection 65 resting on the pin 70. The spring 54, being unopposed by the magnet then exerts a pull on the armature and pawl to

drive the pendulum through pin 70 to the left until the pawl is disengaged from the pin as set out above.

A weight 75 is adjustable on a screw threaded rod 76 to shift the center of gravity 70 of the pendulum for controlling the period of free oscillation thereof.

The operation will be apparent from the above description. On each right hand beat of the pendulum the push rod 26 through the action of its pin 28 on the teeth of the toothed wheel 30 causes the wheel to be rotated through the distance of one tooth space. The dog 34 holds the wheel from reverse movement after each step. Once for each revolution of wheel 30, and while pendulum 13 is swinging to the right on a right beat, contact 38 makes connection with contact 40 causing magnet 51 to be energized. Closure of these switch contacts also energizes the magnets of secondary devices in circuit 49, in case such secondary devices are connected. Energization of magnet 51 pulls armature 55 upwardly against the forces of gravity and spring 54. The attracted position of the armature is indicated in dotted lines. This movement causes pawl 60 to move upwardly and also to the left due to the action of spring 62 against the lower side of support 17. When thus moved to the left the projection 65 on the pawl comes in the path of pin 70 as the same moves upwardly. Before the end of the upward movement of pin 70 the circuit is broken and the spring 54 then acts through the armature, pawl and pin to exert a driving force on the pendulum tending to move it to the left with renewed momentum. After the armature moves a certain distance it is stopped by pin 58 thus allowing pin 70 in its continued movement to release pawl 60 and permit it to drop out of the path of the pin 70. On the next and subsequent movements until magnet 51 is again attracted the pawl 60 remains out of the path of pin 70.

Thus it will be seen that the driving mechanism provided acts on the pendulum in such a way as to engage it, drive it, and release it, with the least interference with its free oscillation. It also acts at such intervals that what interference is interposed is so infrequent that its effect is negligible. This latter point will be more readily accepted as true when it is pointed out that it is easier to accurately measure out one large impulse than it is to measure out sixty small impulses.

While this clock has been described as being adapted to control secondary devices, it will be understood that it may be used as an independent unit apart from such secondary devices.

It will also be understood that the various elements and component parts may be differently arranged and modified in vari-

ous ways within the spirit of the invention as set forth in the appended claims.

Having thus described the invention what is claimed as new and desired to be secured by Letters Patent is:

1. A pendulum operated device comprising, in combination, a compound pendulum pivotally supported at its mid-portion, a push rod carried by said pendulum, a rotatable toothed wheel adapted to be given a step by step movement by said push rod, a contact rotatable with said wheel and adapted to engage a second contact once in each revolution of the wheel, an electro-magnet situated adjacent the pendulum, an armature operated by said magnet, adapted to engage the pendulum when moving in one direction and to drive the pendulum when moving in the other direction, said magnet being energized to move the armature when the toothed wheel has caused the contacts to engage. 50
  2. A pendulum operated device, comprising in combination, a compound pendulum pivotally supported at its mid-portion and means for periodically imparting renewed momentum to said pendulum, said means comprising an electro-magnet, an armature operated by the magnet, said armature having means for engaging the pendulum when moving in one direction in unison with the pendulum and imparting momentum to the pendulum on the return movement of the pendulum and armature, a stop for limiting the movement of the armature on the return movement before the pendulum has completed its movement, to cause said armature to be disengaged from the pendulum, and means for energizing said magnet including a switch which is periodically closed and opened by movement of said pendulum. 55
  3. A device of the character described, comprising in combination, a pendulum, a pin rigid with the pendulum, and mounted on the pendulum so as to have a generally vertical movement, a periodically operated bar adapted to impart renewed momentum to said pendulum, and means on said bar adapted to engage said pin on its upstroke during one beat of the pendulum and to actuate the pendulum and disengage the pin on the succeeding down-stroke, said means comprising a pawl pivoted to said bar, a projection on the pawl for engaging the pin, a flexible projection on the pawl for engaging a relatively immovable stop to bias the pawl toward the pin for causing the notch to engage the pin, a fixed stop to limit the movement of the bar before the pendulum has completed its return movement, and an overhanging weight on said pawl to cause it to be disengaged from the pin when the pendulum swings to free the pin from the notch. 60
  4. A device as claimed in claim 3 in which said bar is actuated by an electro-magnet which is energized at periodic intervals by the operation of a switch which is controlled by the movements of the pendulum. 65
  5. A device of the character described comprising in combination, a pendulum, and means for periodically imparting renewed momentum to the pendulum, said means including a pawl which is moved upwardly to engage the pendulum in unison with an upward movement of a portion of the pendulum, and is moved downwardly to actuate and release the pendulum on the downward movement of the portion, and means controlled by continued movements of the pendulum for causing said first mentioned means to be actuated. 70
  6. A device of the character described, comprising in combination a compound pendulum, a projection on the pendulum having approximately vertical movement during the oscillation of the pendulum, means for engaging said projection while it is moving in one vertical direction and to give it an impulse and disengage it while it is moving in the reverse direction, and means controlled by movements of the pendulum for causing said first mentioned means to be actuated. 75
